John K. Love.

UNITED STATES PATENT OFFICE.

JOHN K. LOVE, OF SILVERTON, ASSIGNOR OF ONE-THIRD TO ELMORE CAMERON, OF CINCINNATI, OHIO.

HINGE FOR RULES AND PROTRACTORS.

SPECIFICATION forming part of Letters Patent No. 512,199, dated January 2, 1894.

Application filed April 10, 1893. Serial No. 469,737. (No model.)

To all whom it may concern:

Be it known that I, JOHN K. LOVE, a citizen of the United States, and a resident of Silverton, in the county of Hamilton and State 5 of Ohio, have invented certain new and useful Improvements in Lock-Hinges for Rules and Protractors, of which the following is a specification.

The several features of my invention and 10 the various advantages resulting from their use, conjointly or otherwise, will be apparent from the following description and claims.

In the accompanying drawings making a part of this specification, and in which like 15 letters of reference indicate corresponding parts,—Figure 1 is a side elevation of a rule illustrating my invention, the rule shown open. Fig. 2 is a side elevation of said rule, closed. Fig. 3 is a side elevation of the same 20 rule partly opened, so that the arms make an angle between them of forty five degrees. Fig. 4 is a view of the joint whereby the two arms of the rule are connected together, the upper portion of one arm being 25 removed, and the connection pivot being shown in section. Fig. 5 is a transverse section of the rule taken in the plane of the dotted line 5, 5, of Fig. 1, that side of the section being shown which faces toward the left hand 30 side of the sheet of drawings. Fig. 6 is a view of that portion of the lock joint which belongs to one arm of the rule and slides between the interlocking portions of the other arm. Fig. 7 is an enlarged view of that portion 35 of Fig. 5 which consists of the set screw H and of portions of the rule immediately adjacent thereto.

A represents one arm of the rule, and B the other arm. The proportionate size of 40 either arm to the other may be varied as desired. As one of such arms is usually made narrower and shorter than the other, I have for the purposes of illustration, thus shown the arm B. That end portion of arm B which 45 interlocks with arm A is formed substantially as shown in Fig. 6, viz: Each side of said end portion is recessed leaving a tongue C and a recess K on each side thereof, that is to say, above and below. This tongue has an inclined edge C', ending at a curved edge C''. The latter is present as the outside rim of a

curved slot C³. At the outer end of this curved slot is a straight portion C⁴, at right angles to the length of the said arm B, and the remaining portion C⁵ of the edge of the 55 tongue is in line with and is a continuation of the inner edge of the arm B. An opening C⁶ in the tongue C receives the pivot connection between the arms A and B. The curve of the slot C³ is a true arc described by radius 60 from the center of the pivot opening C⁶.

The mode of making the recess K leaves a raised boundary B', continued in a straight edge B², extending to the adjacent end of the arm. 65

At the inner end of the slot C³ is a circular recess C⁷ whose center is in the central longitudinal line of the said slot, and of a diameter larger than the width of the slot.

The objects of the foregoing construction 70 will be shortly hereinafter described.

The adjacent end of the arm A is formed as follows, viz: The arm A is provided with an extension A², straight on its lower edge A⁵, curved on edge A³, and straight on its upper 75 side A⁴. The curve of the boundary B² of arm B and the curve A³ of the edge A³ of arm A are concentric. When the rule is in operation, the boundary B² slides or moves against the edge A³ and when the rule is a right angled one, the edge B² rests against the straight edge A⁴ of arm A. The end A² is mortised and the adjacent portion of the end of arm A is hereinafter described. The recess D formed 80 by the said mortise receives the tongue C of 85 the arm B. The upper edge of a part of the end of the arm A is cut away so that the edge B³ of the arm B may come into place against it as shown. The corner portion A' of arm B overlaps the end of the edge B³ as shown. 90 The inner edge or bottom of the recess D has an inclined portion D' and a concavely curved portion D'', and these respectively fit against the portions C' and C'' of the tongue C. Concentric with the pivot hole C⁶ of the tongue 95 are the hole D³ of the top or upper partition or side D⁵ of the mortise D and the hole D⁴ of the lower partition D⁶ of the said mortise. The lower hole D⁴ has a screw thread. A pivot E having a screw thread E' is passed 100 through the upper hole and the hole C⁶ of the tongue, and is screwed into the hole D⁴ of the

lower side of the mortise D. This pivot has a head F² preferably beveled on its under side after the manner of the ordinary screw. A convenient means of turning it is by a slot E³, 5 in the head like the ordinary screw. Such conformation of the head allows the screw to be sunk so that the upper surface of the head is flush with the outer surface of the side D⁵ of the mortise.

10 The set screw H for setting the arms of the rule at a given angle is of a novel construction and the construction of the parts it is combined with is also novel, to wit: This set screw H has a screw threaded shank H', 15 engaging a female screw in an opening D⁹ in the lower side D⁶ of the arm A. This shank H' passes up through the curved slots C³, and terminates in an enlarged disk H², whose thickness is not greater than the depth of the 20 recess C⁷ of the curved slot C³, and is of slightly less diameter, so that it can enter said recess. In the under side of the upper side D⁵ of the arm A is a recess D⁷, just wide enough to receive the disk H². 25 This recess D⁷ is curved and extends over the curved slot C³ and concentric therewith. Above this recess D⁷ is a concentric opening D⁸ of less diameter than the said recess, and extending up through the side D⁵. The upper 30 shank or head H³ of the set screw H extends from the disk H² up and into this opening. The preferred means of rotating it (the screw) consists of a slot H⁴ in the head of the latter. Thus both the screw pivot E and the set 35 screw H have the advantage of being operated by a common screw driver.

Obviously the set screw H when once in place, as aforementioned, cannot be withdrawn. Various ways of getting the set screw 40 H in place can be employed.

A preferred means of getting the set screw H in place is by making one of the sides D⁵ or D⁶ removable.

In the present instance, a portion D¹² of the 45 arm A back of the lines D⁵, D² is cut away as far as D¹⁰, and to the thickness of the side D⁵, the latter is also removed with said portion D¹². This plate thus cut off, or a new plate, the equivalent of the aforesaid portion, and 50 in which the two plates D⁵ and D¹⁰ are integral, is substituted. The set screw H is located in position, and the plate D⁵, D¹² is then put in place and secured there preferably by rivets or screws I, I, I.

55 The mode in which my improved instrument operates is at once simple and effective, viz:— The two arms having been united and the pivot E having been put in place, the rule is ready for use. When the rule is to be used

60 as a square, the arms are placed in the position shown in Fig. 1. The set screw H is now screwed down as far as it will go. This operation places the enlargement or disk H² of it, in the recess C⁷ of the tongue C. As the disk H² quite closely fits this recess, the arms of the square are securely and rigidly held in position by this disk. Furthermore the screw

of shank H' causes the disk H² to press the tongue C hard against the lower side D⁶ of arm A and thus aid in causing the arms to remain rigidly in one and the same horizontal plane. When the rule is to be employed to give an angle other than a right angle, the set screw H is unscrewed, and thus raised until the disk H² is elevated out of the recess C⁷. The arms A and B are now moved in reference to each other until they make the desired angle between them. Then the set screw H is screwed down, and thus the disk H² is forced down upon the tongue C, and presses the latter against the lower side D⁶. This sets the arms and they will remain in this position until the set screw H is loosened, and then the arms can be moved with reference to one another. 85

It will be observed that the shank H' of the set screw is at all times in the curved slot C³, and that the disk H² travels above it, the edges of the disk overlapping the slot. The disk H² performs the functions of a rivet 90 at the lower end of the set screw and of an enlarged head on the set screw H. It acts as a clamp, and at the inner end of the slot when in the recess C⁷ acts as a stop.

What I claim as new and of my invention, 95 and desire to secure by Letters Patent, is—

1. A rule having arms A and B, pivoted together, one provided with tongue C having curved slot C³, and the other with mortise D, and provided with curved recess D⁷, and set screw 100 H, having shank H', and disk H² overlapping the curved slot and moving in recess D⁷ as the shank H' moves in the curved slot C³, substantially as and for the purposes specified.

2. A rule having arms A and B, pivoted together, one provided with tongue C, having curved slot C³ and recess C⁷, and the other arm having a mortise D, provided with curved recess D⁷, following the slot C³, and the set screw H having shank H', engaging the side 110 D⁶, and having disk H² received into curved recess D⁷, or recess C⁷, substantially as and for the purposes specified.

3. A rule having arms as A and B, pivoted together, one of the arms having tongue C and a recess K on each side of the tongue, bounded by the raised edge B² and a curved slot C³ in the tongue C, the arm A having the end corner projection A', and mortise D, and the set screw H whose shank is in the slot C³, and 115 engages the side of the mortise D, the boundary B² resting against the end A⁴ and within the end A' of the arm A when the rule is a right angled one, substantially as and for the purposes specified. 120

4. A rule having arms as A and B pivoted together, one of the arms having tongue C, recess K, bounded by curved edge B' and straight edge B², a curved slot C³ in the tongue, and arm A having end extension A² curved, 130 and straight edge A⁴, and end corner lap A', and mortised, the tongue entering said mortise, and pivoted to the arm A by pivot E, and set screw H having screw shank engag-

ing the arm A, and located in curved slot C³, the set screw also having the disk H², and that half of the mortise D next which the disk is located having a recess receiving the disk, 5 disk, substantially as and for the purposes specified.

5. A rule having arms as A and B pivoted together, one of the arms having tongue C, recess K, bounded by curved edge B' and straight edge B², a curved slot C³ in the tongue, 10 and arm A having end extension A² curved, and straight edge A⁴, and end corner lap A', and mortised, the tongue entering said mortise, and pivoted to the arm A by pivot E, 15 and set screw H having screw shank engaging the arm A, and located in curved slot C³, the

set screw also having the disk H², and that half of the mortise D next which the disk is located having a recess receiving the disk, the tongue C having the inclined edge C' and 20 the curved edge C² projecting below the line of the arm B carrying the slot C³, and the back end of the mortise D in arm A provided with the straight edge D' and the curved edge D² respectively impinging against the 25 edges C' and C² of the tongue C, when the rule is made a right angled one, substantially as and for the purposes specified.

JOHN K. LOVE.
